(57) **CLAIM**

We claim the ornamental design for a handle for a multi-function tool, as shown and described.

DESCRIPTION

FIG. 1 is a perspective view of the claimed design.

FIG. 2 is a right side view thereof.

FIG. 3 is a left side view thereof.

FIG. 4 is a front view thereof.

FIG. 5 is a rear view thereof.

FIG. 6 is a top view thereof.

FIG. 7 is a bottom view thereof.

FIG. 8 is a perspective view of the claimed design with a tool extended.

FIG. 9 is a right side view thereof.

FIG. 10 is a left side view thereof.

FIG. 11 is a front view thereof.

FIG. 12 is a rear view thereof.

FIG. 13 is a top view thereof; and,

FIG. 14 is a bottom view thereof.

The broken lines shown in the drawings represent unclaimed portions of the handle for a multi-function tool and unclaimed portions of the environment that form no part of the claimed design.
